S. F. HAPPEL,
SEAL LOCK.
APPLICATION FILED JAN. 19, 1914.

1,111,065.

Patented Sept. 22, 1914.

UNITED STATES PATENT OFFICE.

SAMUEL F. HAPPEL, OF BETHLEHEM, PENNSYLVANIA.

SEAL-LOCK.

1,111,065.

Specification of Letters Patent. Patented Sept. 22, 1914.

Application filed January 19, 1914. Serial No. 813,002.

To all whom it may concern:

Be it known that I, SAMUEL F. HAPPEL, a citizen of the United States, residing at Bethlehem, in the county of Lehigh and State of Pennsylvania, have invented certain new and useful Improvements in Seal-Locks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to locks and more particularly to that class of seal-locks adapted to be applied to the doors of freight cars or the like.

The object of this invention is to provide a seal-lock which shall be so constructed as to be held in locked position by means of a frangible seal, which seal must be broken to release the parts to enable the door to be unlocked.

25 A further object is to provide a seal-lock which shall combine durability, cheapness and strength.

With these and other objects in view, my invention consists in the peculiar combination and arrangement of the various related parts of a seal-lock for freight car doors, as hereinafter described and more particularly pointed out in the appended claims.

Referring to the drawings forming a part 35 of this invention, wherein similar reference numerals indicate similar parts wherever used: Figure 1 is a perspective view of the seal-lock; Fig. 2 is a longitudinal vertical section of the preferred form of this invention; Fig. 3 is a bottom plan view thereof; Fig. 4 is a section on the line 4—4 of Fig. 2; Fig. 5 is a section on line 5—5 of Fig. 2; Fig. 6 is a view of the bolt; and Fig. 7 is a detail view of one of the sections of the 45 casing.

7 indicates a casing, comprising two sections 7^a and 7^b. Section 7^a is provided with a hollow portion 7^c, and in its bottom and near the front edge is an open slot 7^d. The side walls of the slot are beveled at 7^e, and at opposite ends of the slot are inwardly extended flanges 20—20. Slidably supported on the beveled walls 7^e, is a plate 21, which is shorter than the length of the slot 55 7^d, as shown in Fig. 2. On the upper surface of the plate 21, at one end is a beveled

cam 21^a, and near the opposite end of said plate is a beveled opening 23. Between the opening 23 and the beveled cam 21^a, is a finger operating piece 22^a, formed with a vertical opening 22.

The section 7^b is in the form of a block which fits in the hollow portion 7^c. The section 7^b is cut away at one end at 7^f, which with the adjacent walls of the section 7^a, forms a pocket 10, which extends down to the plate 21. In this pocket is a latch block 13, the lower end of which is supported on the plate 21, and is adapted to be operated by the beveled cam 21^a.

70 Between the top of the latch block and the top of a depression in the section 7^a, is a spring 16, which serves to normally press the latch block down onto the plate 21. The latch block is formed with an opening 14, 75 the upper wall of which is beveled as shown at 15, for a purpose to be described.

Section 7^b of the casing is formed with a longitudinal opening 12, and intersecting this opening is a transverse cut or seal receiving recess 17. The ends of the section 7^a are formed with openings 7^x, which are in alignment with the opening 12, as shown clearly in Fig. 2.

A locking pin 28 slides in the openings 12, 85 7^x and 15, to secure the seal in locked position. The pin is provided on one end with a head 24, which bears against a staple 9, formed at its end with an eye, through which said pin passes. The pin is provided with a beveled portion 27, which when the parts are positioned to lock a seal, is engaged by the beveled wall 15 of the opening in the latch block, the opening in the latter being of sufficient diameter to allow 95 said block to be moved up and down in the pocket.

At the smaller end of the beveled portion 27 of the pin is a shoulder 29, which bears against the latch block, when the latter is in 100 locked position, and prevents withdrawal of the pin until the seal is destroyed, as will be described later on.

In operation, assume the pin is withdrawn and the latch block is supported on the cylindrical portion 30 of said pin and the plate 21 is positioned so as to bring the opening 23 into registry with the recess 17. The end of a seal 18, having an opening 19 and a weakened portion 19^a, is inserted through 110 opening 23, and into recess 17, opening 19 registering with the opening 12. Now the

pin 28 is forced inwardly, until the shoulder 29 is back of the latch block 13, whereupon the spring 16 forces said block down and the beveled wall 15 engages the beveled portion 27, and said pin is locked. When in this position the bottom of the block is on the top of plate 21, adjacent the beveled cam 21^a and the seal is effectively locked by the pin.

To remove the seal, the operator simply bends it back and forth several times until it breaks at the weakened point 19^a, then the plate 21 is slid to the left. When the plate is moved, the cam 21^a engages the bottom of the latch block and raises it until the shoulder 29 is free, whereupon the pin 28 can be withdrawn. The slot above the left hand passage 20 is so proportioned that when the end of the pin is withdrawn, the end of the seal in the recess will fall through slot 22 in the finger piece 22^a. The pin is, for convenience, chained to the casing. If, perchance, the pin should stick in the opening, or if it should break, a tool can be inserted in the opening 7^x, in the left hand end of the section 7^a, and said pin can be forced out the opposite end.

The invention is extremely simple, and because of the concealed lock between the pin and block, unauthorized persons cannot manipulate the lock, except by destroying the seal.

What I claim and desire to secure by U. S. Letters Patent, is:

1. In a seal-lock, the combination of a casing formed with a pin receiving opening and a seal recess intersecting said opening, a pin operating in the opening and engaging a seal in the recess, means for locking the pin, and a slide through which the seal passes, said slide having means for releasing the locking means when the seal is destroyed.

2. In a seal-lock, the combination of a casing provided with a seal engaging pin, a spring actuated latch block for locking the pin in the casing, and means only actuated when a seal is destroyed for moving the latch block to permit withdrawal of the pin.

3. In a seal-lock, the combination of a casing formed with a pin receiving opening and a seal receiving opening which intercepts the pin opening, a slide formed with an opening which registers with the seal recess and through which a seal extends, said plate having a second opening adapted to register with the seal receiving recess to permit a destroyed seal to be removed from the casing, a cam on the slide, a pin operating in the pin receiving opening, and means for locking the pin in the casing, said latter

means being operated by the cam to permit withdrawal of the pin.

4. In a seal-lock, the combination of a casing comprising two sections, said casing having a pocket, a pin opening, a recess, and a slot, the pin opening intersecting the recess and the pocket, a latch block in the pocket, said latch block having an opening, the wall of which is inclined, a spring for normally holding the latch block in one position, a pin in the pin opening, said pin having a beveled portion, and a shoulder adjacent thereto, said beveled portion engaging the inclined wall of the opening.

5. In a seal-lock, the combination of a casing having a longitudinal opening, a pocket and a transverse recess intersecting the longitudinal opening, a latch block in the pocket, said block having an opening, a pin operating in the longitudinal opening in the casing and the opening in the block, said pin having a shoulder which, when the pin is in one position, abuts against the block to lock said pin in position, a slide having an opening which registers with the recess in the block to receive a seal pierced by the pin, said slide having a second opening adapted to register with the recess in the casing when the slide is moved, to remove a broken seal from the recess, and means between the slide and the block to move the latter away from the shoulder on the pin, to permit withdrawal of the latter to release the broken seal.

6. In a seal-lock, the combination of a casing provided with a seal engaging device, a spring actuated latch block for locking the seal engaging device in the casing, and means only actuated when a seal is destroyed to engage the latch block and free the seal engaging means to release a seal.

7. In a seal-lock, the combination of a casing formed with an opening, a seal recess intersecting said opening, a seal engaging device operating in the opening and engaging a seal in the recess, means for locking the seal engaging device in the casing, and a slide held into operative relation with the locking means by the seal, said slide having means for releasing the locking means when the seal is destroyed.

In testimony whereof I have signed my name to this specification in the presence of two subscribing witnesses.

SAMUEL F. HAPPEL.
